UNITED STATES PATENT OFFICE.

LEWIS J. ATWOOD AND FREDERICK W. TOBEY, OF WATERBURY, CONNECTICUT, ASSIGNORS TO THE PLUME & ATWOOD MANUFACTURING COMPANY, OF SAME PLACE.

DESIGN FOR A LAMP-BURNER.

SPECIFICATION forming part of Design No. 19,307, dated September 10, 1889.

Application filed July 6, 1889. Serial No. 316,706. Term of patent 7 years.

To all whom it may concern:

Be it known that we, LEWIS J. ATWOOD and FREDERICK W. TOBEY, of Waterbury, in the county of New Haven and State of Connecticut, have invented and produced a new and original Design for Lamp-Burners, of which the following is a specification.

In the drawings, Figure 1 is an elevation of the lamp-burner, and Fig. 2 is a vertical section of the same.

Our design is especially adapted to large lamp-burners, and is for removing the clumsy and objectionable appearance heretofore usual in this class of burners.

The leading feature in this design is an overhanging horizontal ledge projecting beyond a perforated cylinder, so that the lower part of the burner resembles a series of inverted steps, and has a neat artistic appearance without lessening the size of the overhanging portion on which the chimney rests.

The deflector *a* is dome-shaped, as usual and the circular range of chimney-springs *b* are of ornamental open-work also, as usual; but the perforated air-distributer *c* is cylin-

drical and of considerably smaller diameter than the overhanging annular ledge *d*, and at the same time it is larger than the screw-base, so as to produce a marked contrast in the appearance resulting from the relative sizes of the parts *b* and *c* and the screw-base, and at the lower edge of the part *c* is a projecting rib *e*, which enhances the ornamental appearance of the burner.

What we claim is—

The design for a lamp-burner herein shown and described, the same comprising the perforated cylinder *c*, the annular projecting ledge *d* at the top of the cylinder and below the annular range of ornamental open-work *b*, the cylinder *c* being larger than the screw-base, the whole burner having the appearance of inverted annular steps, substantially as shown.

Signed by us this 29th day of June, 1889.

LEWIS J. ATWOOD.

FRED. W. TOBEY.
